JOHN H. CUNTZ, OF HOBOKEN, NEW JERSEY.

ELECTRIC-WAVE TRANSMISSION.

1,026,150.

Specification of Letters Patent.

Patented May 14, 1912.

Application filed April 14, 1905. Serial No. 255,487.

To all whom it may concern:

Be it known that I, JOHN H. CUNTZ, a citizen of the United States, residing at Hoboken, Hudson county, State of New Jersey, have invented certain new and useful Improvements in Electric-Wave Transmission, of which the following is a specification.

his invention relates to means for raising the permeability of magnetic cores of circuits for the transmission of electric waves or varying currents, such as described in my U. S. Letters Patent No. 977,713, issued December 6, 1910, and No. 995,588 issued June 20, 1911. The general subject of electric wave transmission was amply discussed in those patents and so need not be greatly enlarged upon here. In those applications it was shown that when electric waves are transmitted over long circuits they are attenuated in a manner which is indicated by the formula e^{-px} ; that is, at any distance, x , from the origin of the waves, their amplitude will have decreased 25 from unity to e^{-px} , or in that proportion; where e is the base of the Napierian system of logarithms, x is the distance, in any convenient units of length, and p , which may be termed the attenuation constant, is equal to

$$30 \quad \sqrt{\frac{C\omega}{2}([R^2 + L^2\omega^2]^{1/2} - L\omega)}$$

In this formula, C is the electrostatic capacity, R the resistance, and L , the inductance, of the circuit, all per unit length, and ω is equal to 2π times the frequency of the waves. When an electric current is composed of waves of different frequencies, these component waves will be attenuated in different degrees, and the resulting current or combined wave will be not only attenuated but distorted. This is notably the case in telephonic transmission. When the inductance, L , is large compared with the resistance, R , the expression for p becomes

$$40 \quad \frac{R}{2\sqrt{L}}$$

50 which is seen to be independent of the frequency, so that currents made up of waves of different frequencies will have their components attenuated in the same degree, and the combined wave will not be distorted.

It is also seen that by increasing the inductance the attenuation can be minimized.

As set forth in the applications above referred to, I have invented a method for increasing the inductance of a circuit without proportionally increasing its resistance and 60 electrostatic capacity. This I accomplish by winding the conductor in a helical form, and, where desirable, disposing it about a core. I calculate the inductance of the circuit by means of the formula

$$65 \quad L = 4\pi N^2 \mu A, \\ 10^9$$

where L is the inductance in henries; N the turns of the helix per centimeter; l the 70 length of the portion of circuit under consideration in centimeters; μ the permeability of the medium inclosed by the helix, or of the core; and A the cross-sectional area of the core. The importance of making the 75 inductance large has been shown in the above discussion, and, for a given length of circuit, L may be increased by increasing the number of turns of the helical conductor, by increasing the cross-sectional area of the 80 core, or by increasing the permeability of the core. The present application relates to methods for accomplishing the last named result, namely, increasing the permeability of the core.

85 The permeability of a medium, or μ , may be represented by the ratio

$$90 \quad \frac{B}{H'}$$

where B is the magnetic induction, or lines of force per unit cross-section, and H is the magnetizing force. Figure 1 illustrates the relation between H and B for the better grades of iron. H , in gilberts per centimeter, is laid off along the axis $O H$, and B , in gausses, along the axis $O B$. The value of μ , or the ratio

$$95 \quad \frac{B}{H'}$$

100 will vary at different points of the curve, and will be greatest for the steep portion between x and y . With a core of soft iron and with the feeble currents used in telephony, the value of μ will be, say, from 100 to 200, for the magnetizing forces due to my method of disposing the conductors about

the core. But by the present invention I raise the permeability of the core to, say, 2000 or 3000, or over, by means of a continuous magnetizing current which is caused 5 to flow through the main circuit, and the variable telephonic, telegraphic or other signaling currents are then superposed upon this steady current.

Fig. 1 shows a magnetization curve of 10 iron. Fig. 2 shows, in diagrammatic form, a complete metallic circuit on my system, connected to a source of current for magnetizing the core. Fig. 2^a shows, on an enlarged scale, a joint in the core. Fig. 2^b 15 shows a modified form of a joint in the core. Fig. 3 shows, in diagrammatic form, a circuit on my system, with ground return, connected to a source of current for magnetizing the core. Fig. 4 shows, in diagrammatic form, a circuit on my system, with ground return, connected to a source 20 of current for magnetizing the core, and with a different arrangement at the ends of the line from that of Fig. 3.

25 In Fig. 1, O H represents the axis of abscissæ, along which the magnetizing forces, H, are measured. O B is the axis of ordinates on which the values of the magnetic induction, B, are laid off. The curve x y z 30 is a characteristic magnetization curve for iron. In the part of the curve below x, corresponding to low values of H, the angle which it makes with the axis O H is small, and changes in H produce only moderate 35 changes in B, or, in other words, the permeability, μ , which is the ratio

B

H'

40 is moderate. In the portion of the curve between x and y, the angle which it makes with O H is large and small changes in H cause comparatively great changes in B, and 45 the permeability becomes high. For a good quality of iron, the values of H corresponding to this steep part of the curve are, say, from 0.5 to 10 gilberts per centimeter. Beyond y, the iron approaches its saturation 50 point and the curve flattens out, the permeability again becoming low.

In Fig. 2, C is a core of iron or other magnetic material, with its individual wires or strands discontinuous longitudinally and 55 breaking joints at J, J¹, J² and J³; A and A¹ are the outgoing and returning conductors of a complete metallic circuit, wound helically, in opposite senses, about the core C; F is a battery, or other source of direct current, connected with the circuit A, A¹ through the reversing switch N; T is a telephone transmitter, f a battery and P the primary winding of an induction coil for the transmitting apparatus; the secondary winding, S, of this induction coil is in the main

circuit A, A¹. R is a telephone receiver, and μ and s are the two windings of an induction coil which puts the receiver R in inductive relation to the main circuit A, A¹; s being in the main circuit and μ being in the local receiver circuit. In practice there would be, preferably, transmitting and receiving instruments at both ends of the line, but, for the sake of simplicity, these are not shewn in the diagram.

In Fig. 2^a, a joint of the core is shown. The individual wires are insulated from each other, when desirable, by a thin coating of some insulating compound or by their own oxid, and they are discontinuous longitudinally, or in sections, as shown, but the breaks are at different points along the line, so that while the core is discontinuous as regards electric and magnetic conductivity, it is continuous mechanically and is able to 85 bear a tensile strain.

Fig. 2^b, shows another form of joint, in which the individual wires of the core, instead of having butt joints, have lap joints, for the purpose of securing still greater mechanical strength. These joints are those that are described in my Patent No. 977,713, issued December 6, 1910.

In Fig. 3, C is a core of iron or other magnetic material, with its individual wires 95 or strands discontinuous longitudinally and breaking joints at J, J¹, J² and J³; A is a conductor wound helically about the core C, this conductor being of any convenient cross-section and either single or multiple; 100 F is a battery or other source of direct current connected with the conductor, A, through the reversing switch, N, and the impedance, or choke coil V; the battery is also connected with the ground at E², and 105 the main circuit is completed through the impedance or choke coil, V¹, the ground connection at E³ and the earth. f¹ is a battery, or other source of current, for the transmitting end of the system; K is a key; 110 Q is a condenser; N¹ is a reversing switch; and E is a ground connection. I is a galvanometer or other instrument for receiving 115 on recording signals; Q¹ is a condenser; and E¹ is a ground connection. A steady current 120 flows through the main circuit, being reversed, when desirable, with every message, or at other times, and being cut off altogether, if desirable, between messages. The 125 telegraphic, or other, signals are sent by means of the key, K, the charge of the condenser Q being varied and this variation of charge being transmitted through the main conductor A to the condenser Q¹, and thence through the receiving instrument I to earth at E⁴. These signaling currents are prevented from being shunted to earth at E² and E³ by means of the impedance coils V and V¹, which offer a very high resistance 130 to the intermittent or alternating signaling

currents, but do not prevent the flow of the steady magnetizing current. The charges imparted to the condenser Q by the battery f^1 , are also prevented from going to earth at E^2 by the opposition of the battery F , the two batteries being connected so that they are in parallel as regards the main conductor A , but opposed to each other in the local circuit V N E^2 . In order to preserve this relation when the switch N is reversed, the battery f^1 is also provided with a reversing switch N^1 , which is operated simultaneously with N . The two switches may be connected together mechanically, electrically or magnetically, 15 or in other ways so that when one is reversed the other must be reversed also. The condensers Q and Q^1 prevent the steady magnetizing current and earth currents from affecting the transmitting and receiving instruments; and the impedance, or choke coils V and V^1 prevent sudden or momentary earth currents and similar natural disturbances from affecting the line and the terminal instruments. These impedance or choke 20 coils may or may not have magnetic cores, as found most suitable for a given case, and the number of turns of the coils and their resistance will also depend upon circumstances. U is a rheostat; W is an ammeter; 25 m and m^1 are switches for short circuiting, respectively, U and W , or W alone.

In Fig. 4, C is a core of fine wires of iron or other magnetic material; A is a conductor wound helically about this core; F is a 30 battery, or other source of direct current, connected with the conductor A through the reversing switch N ; E^2 and E^3 are earth connections. At the transmitting end of the system, f^1 is a battery; K a key; and P and S the primary and secondary windings of an induction coil, for placing the transmitting apparatus in inductive relation to the main circuit A . I is a galvanometer or other receiving or recording instrument; 35 and p and s are the two windings of an induction coil which puts the receiving instrument in inductive relation to the main circuit A . A continuous current flows through the main conductor A and returns 40 by way of earth, and does not affect the transmitting and the receiving instruments; while the signaling impulses or alternating currents, are transmitted through the induction coils, P , S and p , s , from the transmitting to the receiving instruments. There 45 may be both transmitting and receiving instruments at both ends of the line, and they may be any suitable telegraph, telephone or other instruments. In order to determine 50 the proper strength of the magnetizing current, and the number of turns of the coils, it is necessary first to have a magnetization curve for the particular kind of iron or other magnetic material, that is used for 55 the core, or a table giving the permeability

for different values of H , the magnetizing force. From the curve or table is found the value of H corresponding to the permeability we desire. H , in gilberts per centimeter, is equal to

70

$$\frac{4\pi nC}{10} (=1.257nC)$$

where n is the number of turns of the magnetizing coil per centimeter, and C is the current in amperes. If we wish to have H of a certain value and know the number of turns of the magnetizing coil, the current required will be

75

$$C = \frac{H}{1.257n}$$

If for example, the magnetizing current is sent through the main circuit, as in Figs. 2, 3 and 4, and this circuit is wound so as to have one turn per centimeter, and it is desired to have H equal to 2, then the current will equal

80

$$\frac{2}{1.257 \times 1}$$

90

or, approximately, 1.6 amperes. As the turns of the conductor are not close together and as the magnetic circuit is not completed through paramagnetic material, particularly where the core is divided into sections, longitudinally, there will be some magnetic leakage, and the value of the magnetizing current should be somewhat greater than the figure obtained by the above formula. When the values of H and of the current are fixed, the number of turns of the magnetizing coils may be found by the formula

95

$$n = \frac{H}{1.257C}$$

100

If, for example, I wish to have H equal to 1, and the magnetizing current equal to 1 ampere, the number of turns of the coil per centimeter will equal

110

$$\frac{1}{1.257 \times 1}$$

115

or, approximately, 0.8. In this case the number of turns per centimeter means the average number for that length of the core the permeability of which it is desired to raise; and as there may be considerable magnetic leakage, the number of turns will have to be greater than the figure given by the above formula. The value of the magnetizing force, H , which will give the required permeability will vary with the material of the core, but other things being equal, it is preferable to use the smallest magnetizing current that will give the core adequate permeability, both on the score of economy in the use of current, and in order to minimize heating, and any possible leakage and electrolysis resulting therefrom. The reversal

120

125

130

of the magnetizing current between messages and at other times also tends to prevent the development of leaks and electrolysis.

5. The conductor or conductors may have any suitable form of cross-section, circular, rectangular or any other shape, and may be single or may consist of a number of wires in multiple.

10. While the core is preferably composed of thin wires, I may, in some cases, use thicker wires, or even a solid core.

In the figures I have shown merely conventional telephone and telegraph instruments at the ends of my lines, but it is to be understood that I may use any kind of suitable instruments and may have both transmitting and receiving instruments at both ends of my line. And in general I do not confine myself to the exact constructions shown in the figures.

What I claim and desire to secure by Letters Patent is:

25. 1. In a system of electric wave transmission, the main conductor or conductors disposed about a magnetizable core, and means for modifying the permeability of said core by a current flowing through said conductor or conductors.

30. 2. In a system of electric wave transmission, the main conductor or conductors disposed about a magnetizable core, and means for causing continuous magnetizing cur-

rent to flow through said conductor or conductors.

35. 3. An electric cable having the working conductor or conductors disposed helically about a magnetizable core, and means for raising the permeability of the core by a current flowing through said conductor or 40 conductors.

4. An electric cable having the working conductor or conductors disposed helically about a magnetizable core, with means for causing continuous magnetizing current to 45 flow through said conductor or conductors.

5. An electric circuit having the main conductor or conductors wound about a paramagnetic core so as to constitute a source of inductance with means for causing 50 continuous magnetizing current to flow through said conductor or conductors.

6. A complete metallic circuit, having outgoing and returning conductors wound in opposite senses about a paramagnetic 55 core, and means for causing continuous magnetizing current to flow through said conductor or conductors.

In testimony whereof, I have signed my name to this specification, in the presence 60 of two subscribing witnesses, this 13th day of April, 1905.

JOHN H. CUNTZ.
